UNITED STATES PATENT OFFICE.

HENRY K. SPENCER, OF WATERTOWN, MASSACHUSETTS, ASSIGNOR TO THE BLANCHARD MACHINE COMPANY, OF CAMBRIDGE, MASSACHUSETTS, A CORPORATION OF MASSACHUSETTS.

ABRASIVE-WHEEL DRESSER.

Application filed May 10, 1921. Serial No. 463,252.

To all whom it may concern:

Be it known that I, HENRY K. SPENCER, a citizen of the United States, and a resident of Watertown, in the county of Middlesex and State of Massachusetts, have invented an Improvement in Abrasive-Wheel Dressers, of which the following description, in connection with the accompanying drawings, is a specification, like characters on the drawings representing like parts.

This invention relates to surface grinding machines, and is more particularly concerned with a dresser for the abrasive wheel, and a method of using the dresser during the grinding operation. The invention has special application to a vertical spindle surface grinder of the type which is the subject matter of United States Letters Patent No. 1,182,861, issued to me May 9th, 1916, to which reference may be had for details not shown here.

The invention will be best understood by reference to the following description, when taken in connection with the accompanying drawings of one specific embodiment thereof, while its scope will be more particularly pointed out in the appended claims.

In the drawings:

Fig. 1 is a plan partly in horizontal section of a portion of a grinding machine equipped with a wheel dresser exemplifying my invention;

Fig. 2 is an elevation of the same; and

Fig. 3 is a detail sectional view on line 3—3 of Fig. 2.

Referring to the drawings, and to the embodiment of the invention which is selected for exemplification, there is shown a portion of a grinding machine having a vertical column 4 presenting guides 6 for a wheel head 8, which carries an abrasive wheel 10, herein annular in form, mounted for rotation about a vertical axis lengthwise of the travel of the head. The latter also carries a safety guard 12, which encircles the wheel. The lower end of the wheel operates on the work, and the latter is suitably held on a face plate 13, shown in Fig. 1.

In the present embodiment, the dresser comprises a set of toothed, hardened steel cutters 14, mounted to rotate on a pin 16 and carried by suitable means permitting

the same to travel across the working surface of the wheel. In the present example, this means is a swinging arm 18 suitably secured to a vertical shaft 20, the latter being mounted to turn in a long bearing 22 presented by a bracket 24, the latter being secured to the wheel head as by cap screws 26. A handle 28, also secured to the shaft, provides a convenient means of rocking the latter to swing the dresser carrying arm. Its swinging movement may be limited by appropriate means, herein a pin 30 carried by an arm 18 and cooperating with the wheel guard 12. The latter limits the swing of the arm in an inward direction.

The dresser is adjustable in a direction transverse to its travel when traversing the working surface of the wheel. This is conveniently accomplished in the present instance by providing an adjusting nut 32 having screw-threaded engagement with the shaft 20, and resting upon a collar 34 which in turn rests upon the bearing 22. The collar is fixed against rotation with respect to the shaft, as by a screw 36 presenting a key 38 received in a key-way 40 extending lengthwise of the shaft, whereby the latter is free to slide vertically with respect to the collar, while still held against turning movement with relation thereto. When, therefore, the adjusting nut 32 is turned in the proper direction, the shaft will be raised or lowered as the case may be, and the cutters 14 adjusted in a direction normal to the working surface of the wheel.

An important feature of my invention is the fact that the dresser can be operated without interrupting the grinding. This is due to the relative location of the dresser, the wheel and the face-plate, it being observed by reference to Fig. 1 that the path of the cutters across the face of the wheel is entirely outside the periphery of the face-plate. If it is observed that the wheel is becoming glazed and not cutting as freely as desired, all that it is necessary to do is to bring the dresser into action by adjusting it to the proper height, and then swinging it to and fro across the working face by the use of the handle provided for that purpose. This furnishes a quick, safe way for dressing or sharpening the wheel, and

it accomplishes the necessary roughening of the wheel face with a minimum loss of the abrasive material.

Having thus described one embodiment 5 of my invention, but without limiting myself thereto, what I claim and desire by Letters Patent to secure is:

1. In a vertical grinding machine, the combination of a horizontal work-support, 10 a vertical abrasive wheel having a lower, horizontal end face which operates on the upper side of work held on the upper face of said work support and having a portion which projects laterally beyond the margin 15 of said work support, a carrier which carries said wheel axially and means also carried by said carrier for dressing said lower, horizontal end face during the grinding operation, comprising a dresser mounted to 20 travel horizontally across and beneath the laterally projecting portion of said end face.
2. In a vertical grinding machine, the combination of a horizontal work-support, a vertical abrasive wheel having a lower, 25 horizontal end face which operates on the upper side of work held on the upper face of said work-support and having a portion which projects laterally beyond the margin of said work-support, a support which 30 carries said wheel vertically toward and from said work-support, and means also carried by said wheel-support for dressing said lower, horizontal end face, comprising a dresser carried by said support and mounted 35 to travel horizontally across and beneath the laterally projecting portion of said end face.
3. In a vertical spindle grinding machine, the combination of a work-support having 40 a horizontal face which is adapted to receive the work, a grinding wheel mounted to rotate about an approximately vertical axis and having a lower end face which projects laterally beyond the margin of said work- 45 support and is adapted to operate on said work, and means for dressing said end face, comprising a dresser carried by said support and mounted to travel across the laterally projecting portion of said end face.
4. In a grinding machine, the combination 50 of a rotatable face-plate and an abrasive wheel arranged eccentrically with relation to each other and having faces perpendicular to their axes, the face of said plate receiving the work thereon and the 55 face of said wheel operating on the work, a carrier which carries said wheel axially, and a wheel dresser also carried by said carrier disposed outwardly beyond the margin of said face- 60 plate and mounted to move from without the perimeter of said wheel across the working face thereof.
5. In a grinding machine, the combination 65 of a rotatable face-plate and an abrasive wheel arranged eccentrically with

relation to each other and having faces perpendicular to their axes, the face of said plate receiving the work thereon and the face of said wheel operating on the work, a carrier which carries said wheel axially, 70 and a wheel dresser also carried by said carrier pivoted eccentrically with relation to said face-plate to swing across the working face of said wheel.

6. In a grinding machine, the combination of a rotatable face-plate and an abrasive wheel arranged eccentrically with relation to each other and having faces perpendicular to their axes, the face of said plate receiving the work thereon and the 80 face of said wheel operating on the work, a carrier which carries said wheel axially, and a wheel dresser also carried by said carrier pivoted to swing about an axis without the margin of said face-plate and to 85 travel across the working face of said wheel.

7. In a grinding machine, the combination of a rotatable face-plate and an abrasive wheel arranged eccentrically with relation to each other and having faces 90 perpendicular to their axes, the face of said plate receiving the work thereon and the face of said wheel operating on the work, a guard about the perimeter of said wheel, a wheel dresser disposed outwardly beyond the margin of said face-plate and mounted to move from without the perimeter of said wheel across the working face thereof, and means cooperating with said guard outwardly beyond said perimeter to limit the inward movement of said wheel dresser and to prevent interference of said wheel dresser with said face-plate. 95

8. In a grinding machine, the combination of a rotatable face-plate and an abrasive wheel arranged eccentrically with relation to each other and having faces perpendicular to their axes, the face of said plate receiving the work thereon and the face of said wheel operating on the work, a wheel dresser disposed outwardly beyond the margin of said face-plate and mounted to move from without the perimeter of said wheel across the working face thereof, and means outwardly beyond said perimeter to 105 limit the inward travel of said wheel dresser with reference to the perimeter of said face-plate. 110

9. In a grinding machine, the combination of an abrasive wheel, a travelling wheel 120 head on which said wheel is mounted for rotation about an axis lengthwise of the travel of said head, a wheel dresser, a shaft on which said wheel dresser is mounted to swing about an axis substantially parallel 125 with the axis of rotation of said wheel, and screw means for adjusting said shaft lengthwise.

10. In a grinding machine, the combination of an abrasive wheel, a travelling wheel 130

- head on which said wheel is mounted for rotation about an axis lengthwise of the travel of said head, a wheel dresser, a shaft by which said wheel dresser is carried about an axis substantially parallel with the axis of rotation of said wheel, and means for adjusting said shaft lengthwise.
11. In a grinding machine, the combination of an abrasive wheel, a travelling wheel head on which said wheel is mounted for rotation about an axis lengthwise of the travel of said head, a wheel dresser, a shaft by one end of which said wheel dresser is carried about an axis substantially parallel with the axis of rotation of said wheel, and means at the other end of said shaft for turning said shaft about its axis.
12. In a grinding machine, the combination of an abrasive wheel having a working surface transverse to its axis, a wheel head on which said wheel is mounted for rotation, a wheel dresser, an arm carrying said wheel dresser, a shaft to which said arm is secured, a bearing carried by said head and in which said shaft is mounted to turn about an axis parallel with the axis of said wheel, a handle secured to said shaft to turn the latter and carry said arm and dresser to and fro, means to limit swinging movement of said arm, an adjusting nut threaded onto said shaft to adjust the latter lengthwise in said bearing, and a collar interposed between said nut and bearing and having splined connection with said shaft.
13. In a grinding machine, the combination of an abrasive wheel, a support therefor, a wheel dresser, a shaft by which said
- wheel dresser is carried across an end face of said wheel about an axis substantially parallel with the axis of said wheel, and means for causing lengthwise movement of said shaft to urge said dresser against said face.
14. In a grinding machine, the combination of an abrasive wheel, a support therefor presenting a bearing substantially parallel with the axis of said wheel, a shaft journaled in said bearing, two arms which are carried by said shaft and project in different directions therefrom, and a dresser carried by one of said arms across an end face of said wheel.
15. In a vertical spindle grinding machine, the combination of an abrasive wheel the lower end face of which operates on the work, a wheel head which carries said wheel vertically, a shaft carried by said wheel head and having its axis disposed lengthwise of the axis of said wheel, and a wheel dresser carried by said shaft across said face.
16. In a vertical spindle grinding machine, the combination of an abrasive wheel the lower end face of which operates on the work, a wheel head which carries said wheel vertically, a lateral wheel guard carried by said wheel head and terminating at its lower end above said face, and a wheel dresser supported by said wheel head for swinging movement transversely beneath the lower end of said wheel guard and across said lower end face of said wheel.

In testimony whereof, I have signed my name to this specification.

HENRY K. SPENCER.
